UNITED STATES PATENT OFFICE

169,880

PRACTICE GOLF CLUB

Edwin H. Williams, Louisville, Ky.

Application December 31, 1952, Serial No. 22,950

Term of patent 7 years

(Cl. D34—5)

To all whom it may concern:

Be it known that Edwin H. Williams, a citizen of the United States, residing in Louisville, county of Jefferson, State of Kentucky, has invented a new, original, and ornamental Design for a Practice Golf Club, of which the following is a specification, reference being had to the accompanying drawing, forming part thereof, wherein

Fig. 1 is a side view of a practice golf club, showing my new design.

Fig. 2 is an end view thereof, looking at the right end in Fig. 1; and

Fig. 3 is a cross-sectional view thereof, taken on line 3—3 in Fig. 1.

I claim:

The ornamental design for a practice golf club, substantially as shown.

EDWIN H. WILLIAMS.
